UNITED STATES PATENT OFFICE.

ANDREW HOWARD, OF WILKINSBURG, PENNSYLVANIA.

DESIGN FOR A GLOBE OR SIMILAR ARTICLE.

SPECIFICATION forming part of Design No. 29,128, dated August 2, 1898.

Application filed June 23, 1898. Serial No. 684,308. Term of patent 3½ years.

To all whom it may concern:

Be it known that I, ANDREW HOWARD, a citizen of the United States, residing at Wilkinsburg, in the county of Allegheny and State of Pennsylvania, have invented a certain new Design for Globes or Similar Articles; and I do hereby declare the following to be a full, clear, and exact description of the invention, such as will enable others skilled in the art to which it appertains to make and use the same.

This invention has relation to globes and similar articles.

The accompanying drawing shows a side view of an incandescent electric-light globe embodying my invention.

The design consists of a globe or similar article having thereon the representation of

the head and a portion of the body of a man clothed in uniform and surrounded by a wreath. On the sides of the wreath are representations of flags, and above the wreath and between the upper portions of the flags is the representation of an eagle with its wings extended.

Having thus described my design, what I claim is—

The design for a globe, or similar article, herein shown and described.

In testimony whereof I affix my signature in presence of two witnesses.

ANDREW HOWARD.
